Primary Examiner—Susan J. Lucas*Assistant Examiner*—Pamela Burgess*Attorney, Agent, or Firm*—Judson D. Cary[57] **CLAIM**

The ornamental design for business paper, as shown and described.

DESCRIPTION

FIG. 1 is a front elevational view of business paper showing my new design;

FIG. 2 is a rear elevational view thereof. The broken lines shown in the drawings represent perforation lines. It is understood that the claimed article is of no substantial thickness; and,

FIG. 3 is a second page of a quadrant bill or invoice or the like.
